(57) **CLAIM**

The ornamental design for a juvenile toothbrush, as shown and described.

DESCRIPTION

FIG. 1 is a front elevation view of the juvenile toothbrush of our new design;

FIG. 2 is a left side elevation view thereof, the right side being a mirror image;

FIG. 3 is a rear elevation view thereof;

FIG. 4 is a top plan view thereof;

FIG. 5 is a bottom plan view thereof;

FIG. 6 is a front perspective view as seen from the bottom left side thereof;

FIG. 7 is a rear perspective view as seen from the bottom right side thereof;

FIG. 8 is a front elevation view of a second embodiment of the juvenile toothbrush of our new design;

FIG. 9 is a left side elevation view thereof, the right side being a mirror image;

FIG. 10 is a rear elevation view thereof;

FIG. 11 is a top plan view thereof;

FIG. 12 is a bottom plan view thereof;

FIG. 13 is a front perspective view as seen from the bottom left side thereof; and,

FIG. 14 is a rear perspective view as seen from the bottom right side thereof.

The broken lines representing bristles in FIGS. 8, 9, and 11-14 are for illustrative purposes only and form no part of the second embodiment.
